2,295,808

TREATMENT OF HYDROCARBONS

Raymond E. Schaad, Chicago, Ill., assignor to
Universal Oil Products Company, Chicago, Ill.,
a corporation of Delaware

Application September 13, 1940, Serial No. 356,594

8 Claims. (Cl. 196—10)

This invention relates to the treatment of hydrocarbon fractions of low antiknock value such as straight-run gasolines and naphthas produced from paraffinic and naphthenic crudes or from any other source for the purpose of producing therefrom substantially saturated motor fuel of relatively high antiknock value.

In a more specific sense the invention is concerned with a process for converting essentially paraffinic and naphthenic hydrocarbons into a gaseous product rich in isobutane, an intermediate product containing branched chain pentanes and hexanes, and a higher boiling liquid product which may be dehydrogenated to normally liquid olefinic hydrocarbons utilizable for alkylating said gaseous product rich in isobutane to form a substantially saturated alkylate of improved antiknock value. Said substantially saturated alkylate may be increased further in antiknock value by a moderate addition of lead tetraethyl.

The formation of isobutane and of other isoparaffins or more highly branched chain paraffin hydrocarbons from less branched chain liquid paraffins and from naphthenic hydrocarbons is desirable because of the generally higher antiknock value of the isomeric paraffin hydrocarbons so formed. Furthermore, the branched chain paraffins, both gaseous and liquid, are generally more reactive than the corresponding normal hydrocarbons and consequently these may be utilized in the production of other branched chain paraffins by so-called alkylation reactions in the presence of suitable catalysts.

In one specific embodiment the present invention comprises a process for converting a substantially saturated liquid hydrocarbon fraction of relatively low antiknock value into a substantially saturated motor fuel of improved antiknock value which comprises treating said hydrocarbon fraction with aluminum chloride, hydrogen, and hydrogen chloride to produce substantial yields of isobutane, a fraction containing branched chain pentanes and hexanes, and a higher boiling hydrocarbon fraction; catalytically dehydrogenating said higher boiling hydrocarbon fraction to form a substantial yield of normally liquid olefins; and subjecting said isobutane and said normally liquid olefins to catalytic alkylation to form a substantially saturated alkylate comprising essentially hydrocarbons of motor fuel boiling range and high antiknock value.

The substantially saturated hydrocarbons preferred as charging stock for the process of this invention and comprising essentially paraffins and naphthenes are normally liquids with relatively

5 low antiknock values. Such substantially saturated hydrocarbons are recovered in considerable quantities in the oil refining industry by distillation of paraffinic, naphthenic, and mixed base crudes. Further, paraffins occur in substantial amounts in other gasolines and in the higher boiling constituents of natural gas commonly known as "casing head gasoline", in certain hydrocarbon materials produced synthetically, and in gasolines produced in relatively high yields by the cracking of relatively heavy petroleum fractions. In the case of cracked gasolines produced from paraffinic and naphthenic oils, the relative proportions of isoparaffins, normal paraffins, and naphthenes may vary over a considerable range.

10 An important feature of the present invention is the use of a superatmospheric hydrogen pressure from about 300 to about 2500 pounds per square inch in the treatment of normally liquid paraffinic and naphthenic hydrocarbons in the presence of substantially anhydrous aluminum chloride at a temperature within the approximate limits of 100° and 500° F. In the absence of an added hydrogen-containing gas, isomerization and destructive hydrogenation reactions are accompanied by the formation of undesirable products, rapid sludge formation on the aluminum chloride catalyst, and an early decrease in catalytic activity.

15 It appears that anhydrous aluminum chloride as generally obtainable contains a small but necessary percentage of hydrogen chloride and/or of oxygen compounds, such as hydroxy-aluminum dichloride, or other oxygen derivatives formed by the reaction of pure aluminum chloride with relatively minor proportions of water or of other oxygen compounds. Further, it has been found advisable to add small but definite quantities of 20 hydrogen chloride to the hydrocarbon fraction being contacted with the aluminum chloride-containing catalyst in order to prevent fouling of the catalyst and a consequent diminution in its hydrocarbon converting activity.

25 30 35 40 45 According to the process of the present invention, it has been found that substantially anhydrous aluminum chloride may be subjected to contact with a hydrocarbon fraction comprising essentially paraffins and naphthenes at an elevated temperature and under a hydrogen pressure in the presence of hydrogen chloride to convert into isoparaffins a substantial proportion of the fraction charged and to produce simultaneously a substantial yield of isobutane. The use of superatmospheric hydrogen pressure is of con-

siderable importance in effecting hydrocarbon conversion reactions in the presence of aluminum chloride because of its effect in prolonging the active life of the catalyst and in reducing substantially what may be termed auto-destructive alkylation, a conversion whereby portions of the hydrocarbons undergoing treatment are converted into higher boiling as well as lower boiling hydrocarbons. The process of this invention effects desired production of isobutane and of higher boiling iso-paraffins with a relatively small amount of auto-destructive alkylation, a conversion which not only reduces the yields of the desired products, but also results in a substantial conversion of the catalyst into a sludge-like material with relatively low catalytic activity.

Continuous destructive hydrogenation of naphtha may be effected by passing the naphtha through a reactor where it may be subjected to contact with hydrogen, hydrogen chloride, and aluminum chloride or a mixture of aluminum chloride with a member selected from the group of so-called Friedel-Crafts' catalysts consisting of ferric chloride, zinc chloride, zirconium chloride, and boron fluoride. Or, the destructive hydrogenating catalyst may consist of a so-called Friedel-Crafts' catalyst selected from the group consisting of ferric chloride, zinc chloride, zirconium chloride, and boron fluoride.

To the hydrocarbon fraction being treated it is preferable to add an amount of hydrogen chloride usually within the limits of 0.5-10% by weight of said hydrocarbon fraction, since continuous operation may otherwise remove small but desirable amounts of hydrogen chloride often present as impurity in substantially anhydrous aluminum chloride available commercially. Because of the shorter time of contact of the hydrocarbon fraction with the catalyst in such continuous conversions, the operating temperature used is generally higher than that required to effect a similar change in batch operations. After such treatment which may be in liquid, vapor, or mixed phase, depending upon the hydrocarbon treated and the temperature and pressure conditions employed, the hydrocarbon material may be removed from the catalyst and fractionally distilled to separate selected fractions of conversion products while unconverted or incompletely converted fractions comprising essentially those boiling above hexane may be subjected to dehydrogenation to form olefinic hydrocarbons utilizable in alkylating isobutane formed in the destructive hydrogenation step of the process as hereinabove set forth.

Destructive hydrogenation products boiling above butanes may be separated into a pentane-hexane mixture and a higher boiling substantially saturated fraction containing heptanes and higher boiling paraffins. Said fraction containing heptanes and higher boiling paraffins may be subjected to contact with a dehydrogenating catalyst preferably in the presence of from about 0.1 to about 10 mole per cent of water vapor at a temperature between about 800° and 1200° F. under a pressure of from substantially atmospheric to approximately 150 pounds per square inch to form a product containing a substantial proportion of normally liquid olefins. Naphthenic hydrocarbons present in the fraction so subjected to dehydrogenation may be converted simultaneously into aromatic hydrocarbons. It is preferable to have a hydrogen-containing gas present in the mixture being contacted with the dehydrogenating catalyst which may comprise a

composite of a substantially inert carrier selected from the group consisting of alumina, magnesia, silica, thoria, titania, zirconia, and zinc oxide, and a relatively smaller proportion of an oxide of an element selected from the members of the left-hand columns of groups V and VI of the periodic table consisting of vanadium, columbium, tantalum, chromium, molybdenum, tungsten, and uranium.

The carriers or supports above referred to have relatively low catalytic activity while the oxides of the elements mentioned, which may be used singly or as mixtures, are of relatively high catalytic activity and furnish by far the greater portion of observed catalytic effects. The oxides of these several elements vary in any given reaction comprised within the scope of the invention, this variation may be greater in the case of different types of dehydrogenation reactions.

The isobutane obtained by destructive hydrogenation of the naphtha or other hydrocarbon fraction charged may be alkylated by the normally liquid olefins formed in the dehydrogenating stage of the process. This alkylation may be carried out in the presence of a suitable catalyst such as sulfuric acid, hydrogen fluoride, aluminum chloride with hydrogen chloride, and boron fluoride with hydrogen fluoride at some temperature between about -15° and 210° F. under sufficient pressure to maintain in liquid phase a substantial proportion of the isobutane present. In general from approximately 4 to about 20 molecular proportions of isobutane or other isoparaffin should be present in the reaction zone for each molecular proportion of olefin introduced thereto to avoid polymerization reactions.

Alkylation of isobutane by a normally liquid olefin formed as hereinabove set forth may be carried out also in the presence of a phosphoric acid-containing catalyst conveniently employed in the form of a solid mixture or granular pre-calcined composite with a generally siliceous adsorbent such as diatomaceous earth. Such a preferred composite alkylating catalyst is the so-called "solid phosphoric acid" catalyst found useful also in polymerization reactions and described in U. S. Patent No. 1,993,513 and others. In the presence of this phosphoric acid-containing material, isobutane and other isoparaffins may be alkylated by olefins at a temperature within the approximate limits of 600° and 900° F. under a pressure between about 1000 and about 3000 pounds per square inch to form a product containing a substantially saturated alkylate of relatively high antiknock value.

These different alkylating catalysts, which may be used alternatively, are not necessarily equivalent in their action, and the conditions of temperature, pressure, and time employed for any given alkylation are determined by the catalyst, the composition of the reaction mixture, and by other factors.

For the purpose of illustrating the combination of steps characteristic of the present invention, the attached drawing shows diagrammatically a typical process flow for treating paraffinic and/or naphthenic hydrocarbon fractions to produce substantial yields of isobutane, a mixture of branched chain pentanes and hexanes, and a higher boiling fraction which may be catalytically dehydrogenated to olefins utilizable in alkylating said isobutane to form a substantially saturated alkylate of high antiknock value.

Referring to the drawing, a naphtha fraction of relatively low antiknock value comprising es-

sentially paraffins and naphthenes substantially free from olefins and/or aromatics may be introduced through line 1, therein commingled with a mixture of an aluminum chloride-containing sludge formed in the process and a mixture of hydrogen and hydrogen chloride introduced as hereinafter described. From line 1 the commingled materials may be introduced to destructive hydrogenation zone 2 which may comprise a reactor of suitable design in which naphtha may be contacted with aluminum chloride-containing catalyst at a temperature between about 100° and 500° F. and preferably under a superatmospheric pressure within the approximate limits of 300 and 2500 pounds per square inch. Destructive hydrogenation zone 2 may contain mixing devices of suitable design for effecting contact between the hydrocarbons and the aluminum chloride-containing catalyst consisting of aluminum chloride sludge formed in the process recycled through lines 7 and 8 and fresh aluminum chloride introduced through line 3 to destructive hydrogenation zone 2 or alternatively through line 4 to line 1, already mentioned.

The products of destructive hydrogenation may be withdrawn from zone 2 through line 5 to separation zone 6 which may comprise settling, stripping, and fractional distilling equipment of adequate design for separating a used aluminum chloride-containing sludge, a gas containing hydrogen and hydrogen chloride, an isobutane fraction, a mixture comprising essentially branched chain pentanes and hexanes, and a higher boiling fraction of relatively low antiknock value. From separation zone 6 the used catalyst sludge may be directed through line 7 to storage, reactivation, or other treatment, or, if desired, a portion of the used aluminum chloride-containing sludge may be recycled from line 7 through line 8 to line 1, already mentioned, through which a mixture of fresh naphtha and a gas containing hydrogen and hydrogen chloride is being conducted to destructive hydrogenation.

Said gas containing hydrogen and hydrogen chloride separated from the destructive hydrogenation products may be directed from separation zone 6 through line 9 in which it may be commingled with fresh hydrogen chloride admitted from an outside source through line 10 and thence introduced to line 1, already mentioned, through which naphtha is charged to destructive hydrogenation. If desired a portion of the gas containing hydrogen and hydrogen chloride being recycled through line 9 may be discharged therefrom through line 11. Said mixture comprising essentially branched chain pentanes and hexanes may be withdrawn from separation zone 6 through line 12 to storage or to other use. Propane and isobutane may be discharged from separation zone 6 through lines 13 and 14, to storage and further treatment, respectively, as hereinafter set forth.

Unconverted naphtha and products boiling higher than hexanes which may be referred to as C₇ and higher hydrocarbons may be conducted from separation zone 6 through line 15, therein commingled by way of line 21 with hydrogen and light gases formed in the process as hereinafter set forth, and thence admitted to destructive hydrogenation zone 16 which may comprise a reactor or group of reactors containing a suitable dehydrogenating catalyst as aforementioned and maintained at a temperature between about 800 and about 1200° F. under a pressure of from substantially atmospheric to approximately 150

pounds per square inch. Under these conditions normally liquid paraffinic hydrocarbons present may be dehydrogenated to the corresponding normally liquid olefins while naphthenic hydrocarbons may undergo conversion to aromatic hydrocarbons.

If desired, propane being discharged through line 13 may be directed through alternative line 17 to commingle with the mixture being subjected to dehydrogenation in zone 16. The total product may be discharged from dehydrogenation zone 16 through line 18 to separation zone 19 which may comprise absorbing and stripping equipment of adequate design for separating a mixture of hydrogen and light gases, such as methane, ethane, etc., from higher boiling and generally normally liquid hydrocarbons containing olefins formed by dehydrogenation in zone 16 as hereinabove set forth. Said mixture of hydrogen and light gases may be directed from separation zone 19 through line 20 to line 9, already mentioned, through which hydrogen, hydrogen chloride, and light gases are being recycled to further use in destructive hydrogenation zone 2. 20 A portion of said mixture of hydrogen and light gases being directed through line 20 may be conducted therefrom through line 21 to commingle with said unconverted naphtha and products boiling higher than hexanes being conducted to destructive hydrogenation zone 16.

Said hydrocarbons containing olefins separated in separation zone 19 from a mixture of hydrogen and light gases may be directed through line 22 and therein commingled with isobutane, or another isoparaffin, being conducted from separation zone 6 through line 14, already mentioned. The resulting commingled mixture may be directed from line 22 to alkylation zone 23 which may comprise a suitable reactor provided with adequate agitating, cooling, and/or heating devices for maintaining the uniform temperature preferable for alkylation in the presence of a catalyst selected from the group consisting of sulfuric acid, hydrogen fluoride, aluminum chloride with hydrogen chloride, and boron fluoride with hydrogen fluoride at a temperature between about -15° and 210° F. Means not shown may be provided for adding fresh catalyst and for removing used catalyst during the course of the aforementioned 45 alkylation reactions. Also alkylation of isobutane by normally liquid olefins may be effected in the presence of a precalcined composite of an acid of phosphorus and a generally siliceous adsorbent in a reactor or plurality of reactors containing the granular catalytic material and operated at a temperature between about 600° and 900° F. under a pressure within the approximate limits of 1000 and 3000 pounds per square inch.

Normally liquid products formed by such alkylation and admixed with unconverted isobutane and with normally liquid hydrocarbons boiling above hexane which were not dehydrogenated in zone 16 may be discharged from alkylation zone 23 through line 24 to separation zone 25 which may comprise fractional distilling equipment of adequate design for separating a substantially saturated and alkylate-containing motor fuel from unconverted isobutane and lighter gases such as propane which may be present when this gaseous hydrocarbon is admixed with the liquid hydrocarbons being subjected to dehydrogenation as hereinabove set forth. Said unconverted isobutane may be recycled from separation zone 25 through lines 26 and 22 to further alkylation treatment. The motor fuel fraction containing

the substantially saturated alkylate formed in the process may be withdrawn through line 27 to storage while light gases such as propane may be discharged through line 28 to storage or to other use.

If desired, a portion of the substantially saturated hydrocarbons not dehydrogenated in zone 16 and present in said motor fuel may be separated from the alkylation product in separating zone 25 and thence recycled by means not shown to further dehydrogenation treatment in zone 16 in order to provide sufficient normally liquid olefins for alkylating substantially all of the isobutane derived from the primary destructive hydrogenation step of the process.

The following specific example is presented as 15 illustrative of the process as it may be conducted using a process flow as hereinabove described, although this illustrative material should not be misconstrued to limit the generally broad scope of the invention:

A substantially normal paraffin hydrocarbon fraction containing 2% by volume of hexane, 10% heptane, 13% octane, 25% nonane, 20% decane, 20% undecane, and 10% by volume of higher boiling hydrocarbons may be heated at 165° F. in the presence of hydrogen under a pressure of 1600 pounds per square inch and in the presence of 10% by weight of aluminum chloride and 1.2% by weight of hydrogen chloride. The products of this treatment may consist of 25.8% by weight of isobutane; 24.5% of a pentane fraction with 85.5 octane number and approximately 90% isopentane content; 9.7% of a hexane fraction with 80 octane number; 27.2% of a fraction with 5.5 octane number comprising essentially heptanes and higher boiling products; 4.2% of non-condensable gases; 4.9% of hydrocarbonaceous residue; and 3.3% loss.

The fraction comprising essentially heptanes and higher boiling hydrocarbons may be vaporized and commingled with approximately 4 mole per cent of water vapor and the commingled mixture then subjected at 1020° F. under substantially atmospheric pressure to contact with a composite comprising essentially 8% by weight of chromium sesquioxide and 92% by weight of activated alumina to form a product containing substantial proportions of normally liquid olefins.

Isobutane derived from destructive hydrogenation of the paraffinic fraction charged may be alkylated by said normally liquid olefins in the presence of sulfuric acid of 95% concentration at 45° F. under a pressure of 200 pounds per square inch to form a substantially saturated alkylate 50 admixed with heptane and higher boiling hydrocarbons remaining unconverted after the original treatment with the chromium sesquioxide-alumina catalyst. A sufficient proportion of said heptane and higher boiling hydrocarbons may be 55 separated from said motor fuel by fractional distillation and then recycled to further dehydrogenation to produce olefins necessary for alkylating substantially all of the isobutane produced in the primary destructive hydrogenation step.

Thus by combining destructive hydrogenation, dehydrogenation, and alkylation it is possible to obtain approximately 34% by weight of a pentane-hexane fraction of approximately 84 octane number, 45% by weight of a substantially saturated alkylate of gasoline boiling range and 90 octane number, and 10% by weight of a higher boiling residue from a naphtha fraction of relatively low antiknock value.

The character of the process of the present in- 75

vention and particularly its commercial value are evident from the preceding specification and limited numerical material presented although neither section is intended to be unduly limiting in its generally broad scope.

I claim as my invention:

1. A process for converting a substantially saturated hydrocarbon fraction of motor fuel boiling range and relatively low antiknock value into a substantially saturated motor fuel of improved antiknock value which comprises treating said hydrocarbon fraction with aluminum chloride, hydrogen, and hydrogen chloride to produce substantial yields of isobutane, a fraction containing branched chain pentanes and hexanes, and a higher boiling hydrocarbon fraction; catalytically dehydrogenating said higher boiling hydrocarbon fraction to form a dehydrogenation product containing a substantial proportion of normally liquid olefins; and subjecting said isobutane and said dehydrogenation product to catalytic alkylation to form a substantially saturated alkylate comprising essentially hydrocarbons of motor fuel boiling range and high antiknock value.

2. A process for converting a substantially saturated hydrocarbon fraction of motor fuel boiling range and relatively low antiknock value into a substantially saturated motor fuel of improved antiknock value which comprises treating said hydrocarbon fraction with aluminum chloride, hydrogen, and hydrogen chloride at a temperature between about 100° and about 500° F. under a pressure within the approximate limits of 300 and 2500 pounds per square inch to produce substantial yields of isobutane, a fraction containing branched chain pentanes and hexanes, and a higher boiling hydrocarbon fraction; catalytically dehydrogenating said higher boiling hydrocarbon fraction to form a dehydrogenation product containing a substantial proportion of normally liquid olefins; and subjecting said isobutane and said dehydrogenation product to catalytic alkylation to form a substantially saturated alkylate comprising essentially hydrocarbons of motor fuel boiling range and high antiknock value.

3. A process for converting a substantially saturated hydrocarbon fraction of motor fuel boiling range and relatively low antiknock value into a substantially saturated motor fuel of improved antiknock value which comprises treating said hydrocarbon fraction with aluminum chloride, hydrogen, and hydrogen chloride to produce substantial yields of isobutane, a fraction containing branched chain pentanes and hexanes, and a higher boiling hydrocarbon fraction; subjecting said higher boiling fraction to contact with a dehydrogenating catalyst at a temperature between about 800° and about 1200° F. under a pressure of from substantially atmospheric to approximately 150 pounds per square inch to form a dehydrogenation product containing a substantial proportion of normally liquid olefins; and subjecting said isobutane and said dehydrogenation product to catalytic alkylation to form a substantially saturated alkylate comprising essentially hydrocarbons of motor fuel boiling range and high antiknock value.

4. A process for converting a substantially saturated hydrocarbon fraction of motor fuel boiling range and relatively low antiknock value into a substantially saturated motor fuel of improved antiknock value which comprises treating said hydrocarbon fraction with aluminum chloride, hydrogen, and hydrogen chloride at a temperature between about 100° and about 500° F. un-

der a pressure within the approximate limits of 300 and 2500 pounds per square inch to produce substantial yields of isobutane, a fraction containing branched chain pentanes and hexanes, and a higher boiling hydrocarbon fraction; subjecting said higher boiling fraction in the presence of from about 0.1 to about 10 mole per cent of water vapor to contact with a dehydrogenating catalyst comprising essentially a major proportion of a substantially inert carrier and a relatively smaller proportion of an oxide of an element selected from the members of the left-hand column of group V of the periodic table consisting of vanadium, columbium, and tantalum to form a dehydrogenation product containing a substantial proportion of normally liquid olefins; and subjecting said isobutane and said dehydrogenation product to catalytic alkylation to form a substantially saturated alkylate comprising essentially hydrocarbons of motor fuel boiling range and high antiknock value.

5. A process for converting a substantially saturated hydrocarbon fraction of motor fuel boiling range and relatively low antiknock value into a substantially saturated motor fuel of improved antiknock value which comprises treating said hydrocarbon fraction with aluminum chloride, hydrogen, and hydrogen chloride at a temperature between about 100° and about 500° F. under a pressure within the approximate limits of 300 and 2500 pounds per square inch to produce substantial yields of isobutane, a fraction containing branched chain pentanes and hexanes, and a higher boiling hydrocarbon fraction; subjecting said higher boiling fraction in the presence of from about 0.1 to about 10 mole percent of water vapor to contact with a dehydrogenating catalyst comprising essentially a major proportion of a substantially inert carrier and a relatively smaller proportion of an oxide of an element selected from the members of the left-hand column of group VI of the periodic table consisting of chromium, molybdenum, tungsten, and uranium to form a dehydrogenation product containing a substantial proportion of normally liquid olefins; and subjecting said isobutane and said dehydrogenation product to catalytic alkylation to form a substantially saturated alkylate comprising essentially hydrocarbons of motor fuel boiling range and high antiknock value.

6. A process for converting a substantially saturated hydrocarbon fraction of motor fuel boiling range and relatively low antiknock value into a substantially saturated motor fuel of improved antiknock value which comprises treating said hydrocarbon fraction with aluminum chloride, hydrogen, and hydrogen chloride at a tem-

perature between about 100° and about 500° F. under a pressure within the approximate limits of 300 and 2500 pounds per square inch to produce substantial yields of isobutane, a fraction containing branched chain pentanes and hexanes, and a higher boiling hydrocarbon fraction; subjecting said higher boiling fraction in the presence of between about 0.1 and 10 mole per cent of water vapor and a hydrogen-containing gas derived from the process to contact with a dehydrogenating catalyst comprising essentially a major proportion of a substantially inert carrier and a relatively smaller proportion of an oxide of an element selected from the members of the left-hand column of group VI of the periodic table consisting of chromium, molybdenum, tungsten, and uranium to form a dehydrogenation product containing a substantial proportion of normally liquid olefins; and subjecting said isobutane and said dehydrogenation product to catalytic alkylation to form a substantially saturated alkylate comprising essentially hydrocarbons of motor fuel boiling range and high antiknock value.

7. A process for converting a substantially saturated hydrocarbon fraction of motor fuel boiling range and relatively low antiknock value into a substantially saturated motor fuel of improved antiknock value which comprises continuously treating said hydrocarbon fraction with aluminum chloride, hydrogen, and hydrogen chloride to produce substantial yields of isobutane, a fraction containing branched chain pentanes and hexanes, and a higher boiling hydrocarbon fraction; simultaneously catalytically dehydrogenating said higher boiling hydrocarbon fraction to form a dehydrogenation product containing a substantial proportion of normally liquid olefins; and continuously subjecting said isobutane and said dehydrogenation product to catalytic alkylation to form a substantially saturated alkylate comprising essentially hydrocarbons of motor fuel boiling range and high antiknock value.

8. A process for producing anti-knock motor fuel from substantially saturated hydrocarbon oil, which comprises subjecting the oil to catalytic destructive hydrogenation such as to produce a substantial quantity of isobutane, separating from the resultant products an isobutane fraction and a fraction higher boiling than hexane, subjecting the last-named fraction to catalytic dehydrogenation to form normally liquid olefins, commingling the latter with said isobutane fraction, subjecting the resultant mixture to catalytic alkylation to react olefins with isobutane and recovering the resultant alkylate.

RAYMOND E. SCHAAD.
